(57) **CLAIM**

The ornamental design for a sports bar for vehicle, as shown and described.

DESCRIPTION

FIG. 1 is a perspective view including the front, top, and side of a sports bar for vehicle showing my new design; FIG. 2 is a perspective view including the rear, top, and side thereof;

FIG. 3 is a front elevation view thereof;

FIG. 4 is a rear elevation view thereof;

FIG. 5 is a side elevation view thereof;

FIG. 6 is an opposite side elevation view thereof;

FIG. 7 is a top plan view thereof; and,

FIG. 8 is a bottom plan view thereof.

The sports bar for vehicle is shown with a symbolic break in its length; the appearance of any portion of the article between the break lines forms no part of the claimed design.
